CLAIM

The ornamental design for a waterproof camera, as shown and described.

DESCRIPTION

FIG. 1 is a front, right and bottom perspective view of a waterproof camera, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled **9** in FIG. 1; and,

FIG. 10 is a partial enlarged view of an area labeled **10** in FIG. 2.

The broken lines shown in the drawings are included for the purpose of illustrating portions of the waterproof camera that form no part of the claimed design. The dot-dash broken lines in FIGS. 1, 2, 9 and 10 depict the boundaries of the enlargements that form no part of the claimed design.
